R. C. FROHOCK

STARTING DEVICE

Filed March 8, 1922

Inventor

R. C. Frohock

By *Alfred E. Lawson*
Attorney

UNITED STATES PATENT OFFICE.

RODNEY C. FROHOCK, OF AUGUSTA, MAINE.

STARTING DEVICE.

Application filed March 8, 1922. Serial No. 542,179.

To all whom it may concern:

Be it known that I, RODNEY C. FROHOCK, a citizen of the United States, residing at Augusta, in the county of Kennebec and 5 State of Maine, have invented certain new and useful Improvements in Starting Devices, of which the following is a specification.

This invention relates to certain improvements in starting devices for internal combustion engines and has relation more particularly to a device of this general character especially designed and adapted for use in connection with motor driven fire apparatus, and it is primarily an object of the 10 invention to provide a novel and improved means of this general character which automatically operates upon the sounding of an alarm.

20 The invention consists in the details of construction and in the combination and arrangement of the several parts of my improved starting device whereby certain important advantages are attained and the 25 device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:

35 Figure 1 is a diagrammatic view partly in elevation and partly in section illustrating a starting device constructed in accordance with an embodiment of my invention;

40 Figure 2 is an enlarged fragmentary sectional view illustrating the electrically operated lock; and

Figure 3 is a fragmentary view illustrating in detail the coupling means comprised in the device as herein set forth.

45 As disclosed in the accompanying drawings, V denotes a motor driven vehicle and which is provided with a movable member 1 such as a lever which, upon movement in one direction, serves to close the ignition and starter switch for the starting of the 50 motor (not shown).

Secured to the movable member or lever 1 is an end portion of a flexible member 2 which extends within the hood of the vehicle through the dash and which passes over a suitably supported guide member or roller

3. The flexible member 2 extends downwardly from the guide member or roller 3 and has its lower or free extremity provided with an annular member or loop 4, preferably of a rigid type.

When the vehicle V is at its station, the same is disposed over a member 5 hinged, as at 6, to the under surface of the floor F upon which the vehicle V rests. The member 5 is provided with a spring-pressed latch 7 which engages within the keeper 8 also secured to the under surface of the floor F. The coaction between the latch 7 and the keeper 8 serves normally to maintain the member 5 in its raised position.

Arranged within the keeper 8 is a winding 9 with which is associated a solenoid 10. The winding 9 is interposed within the operating circuit 11 for the alarm A, herein disclosed as a bell. When the alarm A is sounded, the winding 9 will be energized to impose outward movement to the solenoid 10, said movement of the solenoid effecting a release of the latch 7 from the keeper 8 so that the member 5 will drop. To facilitate the dropping of the member 5 and to provide the desired weight, for the purpose to be hereinafter referred to, a ball 12 or other weighted member is suspended from the member 5.

Secured, as at 14, to the member 5 is a flexible member 15 which extends upwardly through an opening 16 in the floor F. The upper or free end portion of the member 15 is secured to a tension spring clamp 17 which engages the loop or member 4, hereinbefore referred to, when the vehicle V is at its station. When the member 5 drops, sufficient pull will be imposed upon the movable member or switch lever 1 to close the ignition and starter switch for the motor, thus permitting the warming up of the motor without an instant delay upon the sounding of the alarm. As the car moves, the tension clamp 17 will readily disengage from the loop or member 4.

From the foregoing description it is thought to be obvious that a starting device constructed in accordance with my invention is particularly well adapted for use by reason of the convenience and facility with which it may be assembled and operated, and it will also be obvious that my invention is susceptible of some change and modification without departing from the principles and spirit thereof and for this reason I do not

2
wish to be understood as limiting myself to the precise arrangement and formation of the several parts herein shown in carrying out my invention in practice except as hereinafter claimed.

I claim:

In combination with a movable member for closing the operating circuit of a starter of an engine and an alarm circuit, a member 10 supported for swinging movement, a weighted member carried by the swinging member, a flexible member engaged with the movable member, the second flexible member engaged with the swinging member, a tension clamp carried by the second flexible member and engageable with the first named flexible member, means for holding the

swinging member in one position and against movement under the influence of the weighted member carried thereby, means 20 operatively engaged with the alarm circuit for releasing said holding means upon sounding of the alarm to permit the weighted member to drop, the dropping of the weighted member imposing sufficient pull upon the 25 first named flexible member to move in closed position the member for closing the operating circuit of the starter, the tensioning clamp disengaging the first named flexible member upon pull being imposed upon the first named flexible member in addition to the pull created by the weighted member.

In testimony whereof I affix my signature.

RODNEY C. FROHOCK.
